UNITED STATES PATENT OFFICE.

WILLIAM D. P. AIMS, OF PHILADELPHIA, PENNSYLVANIA.

APPARATUS FOR DISTILLING HEAVY HYDROCARBONS, SHALE, AND THE LIKE.

1,405,704.

Specification of Letters Patent. Patented Feb. 7, 1922.

Application filed November 15, 1920. Serial No. 424,010.

To all whom it may concern:

Be it known that I, WILLIAM D. P. AIMS, a citizen of the United States, residing at Philadelphia, in the county of Philadelphia and State of Pennsylvania, have invented a new and useful Apparatus for Distilling Heavy Hydrocarbons, Shale, and the like, of which the following is a specification.

The principal objects of the present invention are, first, to provide an apparatus for distilling heavy hydrocarbons, requiring a cracking or carbonizing temperature which will not be clogged or stopped by the resulting coke or solid carbon and which may be operated continuously; second, to provide simple, efficient and easily controllable apparatus for distilling or evaporating hydrocarbons from oil bearing shale, rock, sands, heavy hydrocarbons and other viscous material; and third, to provide an apparatus of the kind specified in which heat is economically applied and in which large quantities of material can be treated at the same time so that quantity production is effected. Other objects of the invention as well as its principal features will appear from the following description at the end of which the invention will be claimed.

Reference will be made to the accompanying drawings, forming part hereof, and in which—

Figure 1, is a side view principally in section of an apparatus embodying features of the invention.

Fig. 2, is a top or plan view partly in section of the same, and

Figs. 3 and 4, are sectional views taken on the lines 3—3 and 4—4 of Figure 1.

In the drawings 1 is a shell or housing equipped to retain heat as by means of a heat insulating lining 2. This shell 1, is horizontally divided into a rectangular heating chamber 3 below, and a pyramidal vaporizing chamber 4 above, by a partition. This partition consists of a plate or floor 5, extending across the shell 1 and provided with vertical walls 6. The partition or plate 5, is provided with a series of parallel slots in which conveyor screw troughs 7 are arranged so as to extend between the end walls 6. The troughs 7 are shown as suspended by flanges on their elongated side walls 8, and as closed at their ends by the end walls 6, so that the upper and lower chambers are separated by the plate 5, the end walls 6, and the troughs 7. From one

of the ends of each trough 7 there extends a screw conveyor inlet casing 8 which is fitted through the end wall of the shell 1 and connected through the wall 6, and which is also provided with a feed hopper 9. The feed hoppers 9, are made to adjoin so that they can be filled by a crosswise traveling car or conveyor or otherwise without waste of material. From the other end of the troughs 7 there extends a series of similar screw conveyor outlet casings 10, which discharge onto a cross conveyor apron 11, arranged in a suitable housing 12. 13 are a series of conveyor screws and they extend along the troughs 7 and through the screw conveyor casings 8 and 10, of which the ends are closed by caps 14, and bearing pieces 15 constituting packing boxes. The casings 8 and 10, and the screws 13 are long enough to contain sufficient comminuted material for preventing the escape of the distillate through these casings. 16 and 17 are sleeves and rings for connecting up and supporting the sections which make up the casings. 18 are inlet pipes arranged beneath the troughs 7, and by which superheated steam or combustible fuel is introduced for heating the contents of the troughs, and 19 is an off-take or exhaust connection. 20, are pyrometers by means of which the heating of the troughs is controlled through the regulation of the valves 21 and 22. The screw conveyor shafts 23, extend through the packing boxes 14 and 15, at the ends of the inlet casings 8, and are geared together by toothed wheels 24, and idlers 25, and this train of gears is driven by tight and loose pulleys 26. 27 are columns for supporting the structure, 28 are man and sight-holes, and 29 is an off-take for the distillate or vapor.

The solid material to be distilled, in comminuted form, or heavy hydrocarbon is fed into the hoppers 9 and the feed screws 13, working in unison continuously carry it through the casings 8, and through the troughs 7, where it is exposed to regulated heat and gives up its vaporizable oil content, which is led off from the off-take 29. From the troughs the material is carried through the casings 10, and discharged onto the conveyor 11, which may simply deposit it upon a dump, or carry it to another similar distilling apparatus, and in the latter case the distillation may be a fractional one. Evidently a large bulk of material is treated at the same time, although each screw may

feed only comparatively little of it, and the fact that all of the material is treated in one large shell effects an economy in the use and application of heat, and the provision of a controllable heating means for each trough permits of a proper distribution of the applied heat.

- Carbon, usually in the form of coke, resulting from such high temperatures as are intended to be used in the described apparatus, does not choke the apparatus because the conveyor screws keep the mass stirred and broken up, so that the carbon is continuously fed out through the casings 10. 15 The high side walls 8^a, of the troughs permit the mass to rise without escaping from the troughs and cause the mass to fall back on the conveyor screws which carry it out of the machine. In case of an accidental jam, 20 the same can be released by tools inserted through the openings 28. In consequence of the continuous removal of the coke the apparatus may be operated without interruption for cleaning it.

25 I claim:

1. Apparatus for distilling heavy hydrocarbons comprising the combination of a shell having a distillate off-take, a plate arranged across the shell, a series of troughs 30 having extended side walls and forming with the plate a partition dividing the shell into upper and lower chambers and open to the upper chamber, conveyor-screw casings extending from the ends of the troughs outside of the shell, conveyor screws in the troughs and casings, and individual heating means below the troughs and all enclosed in the lower chamber, substantially as described.
- 40 2. Apparatus for distilling heavy hydrocarbons comprising the combination of a shell having a distillate off-take, a plate arranged across the shell, a series of troughs 45 having extended side walls and forming with the plate a partition dividing the shell into upper and lower chambers and open to the upper chamber, conveyor-screw casings extending from the ends of the troughs outside of the shell, conveyor screws in the 50 troughs and casings, individual heating means below the troughs and all enclosed in the lower chambers, a row of hoppers adjoining each other and feeding into the inlet conveyor-screw casings, and a cross-conveyor 55 onto which all the outlet conveyor-

screw casings discharge, substantially as described.

3. Apparatus for distilling heavy hydrocarbons comprising the combination of a shell having an enclosed heating chamber 60 below and a separate enclosed distillate chamber above, troughs having their bottoms exposed to the heating chamber and their tops open to the distillate chamber, means in the heating chamber for applying 65 heat to the bottoms of the troughs, screw-conveyors in the troughs for breaking up and removing coke, and screw-conveyor casings extending beyond and outside of the shell and into which the screw-conveyors extend to oppose the escape of distillate, substantially as described.

4. Apparatus for distilling heavy hydrocarbons comprising the combination of a shell having an enclosed heating chamber 75 below and a separate enclosed distillate chamber above, troughs having their bottoms exposed to the heating chamber and their tops open to the distillate chamber, means in the heating chamber for applying 80 heat to the bottoms of the troughs, screw-conveyors in the troughs for breaking up and removing coke, screw-conveyor casings extending beyond and outside of the shell and into which the screw-conveyors extend 85 to oppose the escape of distillate, a train of gear wheels arranged at the ends of the inlet casings for driving the screws in unison, and a conveyor onto which the outlet casings discharge through lateral openings 90 provided in their cylindrical walls, substantially as described.

5. Apparatus for distilling heavy hydrocarbons comprising the combination of a generally rectangular heating chamber, a 95 pyramidal distillate chamber superposed on the heating chamber, a partition separating said chambers and having end walls spaced from the corresponding walls of the heating chamber, troughs of which the ends are 100 stopped by the end walls and which depend from the partition and open into the distillate chamber, screw-conveyor casings opening through the end walls into the troughs and passing through and beyond the walls of the 105 heating chamber, screw-conveyors in the casings and troughs, and means in the heating chamber for heating the troughs, substantially as described.

WILLIAM D. P. AIMS.
